(57) **CLAIM**

The ornamental design for a torso protector, as shown and described.

DESCRIPTION

FIG. 1 is a front view of the torso protector embodying the design;

FIG. 2 is a rear view thereof;

FIG. 3 is a left-side view thereof;

FIG. 4 is a right-side view thereof;

FIG. 5 is a top view thereof; and,

FIG. 6 is a bottom view thereof.

The broken lines in FIGS. 1 to 6 show elements and areas that are part of the environment of the design and form no part of the design claimed.
